(57) **CLAIM**

The ornamental design for a safety pin keyring, as shown and described.

DESCRIPTION

FIG. 1 is a front elevational view of the safety pin keyring showing my design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front perspective view thereof; and,

FIG. 8 is a front perspective view thereof with the pin unfastened from the clasp.

The phantom lines shown in the Figures are illustrative of environmental structure only and form no part of the claimed design.
